UNITED STATES PATENT OFFICE

2,476,692

FAN

Samuel M. Bernstein, Chicago, Ill.

Application December 18, 1947, Serial No. 792,561

5 Claims. (Cl. 230—273)

1

The invention relates to fans and more particularly to fans which are installed in a wall opening or window.

It is an object of the invention to provide a fan which may be selectively employed either as a ventilating or exhaust fan.

A further object constitutes the provision of means for conveniently converting the ventilating fan into an exhaust fan and vice versa.

It is a further object to provide means extraneous to the housing of the fan to arrange the fan for ventilation or exhaust.

It is also an object to provide certain features of construction and arrangement of parts tending to enhance the utility and efficiency of a device of the character specified.

With these and other objects in view which will become apparent from a disclosure of the invention, the latter comprises the means described in the following specification particularly pointed out in the claims forming a part thereof, and illustrated in the accompanying drawing, in which

Fig. 1 is a front view of a fan constructed in accordance with my invention.

Fig. 2 is a rear view.

Fig. 3 is a top plan view.

Fig. 4 is an enlarged section on the line 4—4 of Fig. 1.

Fig. 5 is a partial top plan view as from line 5—5 of Fig. 4, and

Fig. 6 is an isometric view of the upper end of the supporting shaft.

Fig. 7 is a top plan view of a modification.

Fig. 8 is a section on the line 8—8 of Fig. 7 on a reduced scale, and

Fig. 9 is an isometric view of the upper end of the supporting shaft.

Referring to the several views in the drawing 10 designates a wall plate which at its outer end is bent at right angles to provide a flange 11. The terminal end of said flange is folded upon itself as at 12 to overlap a flange 13 of reinforcing plates 14. The plates 14 have large semi-circular cut-out portions 15 at the meeting edges to provide a circular opening for a purpose presently to be described. The plates 14 may be secured to the wall plate 10 by screws or rivets 14a.

The wall plate 10 is formed with a large circular opening 16 and the edge of said opening is bent outwardly to provide a circumferential flange 17. The opening defined by the reinforcing plates 14 and the opening 16 are concentric. A casing 18 is secured to the wall plate by being

2

provided with flange 19 which is welded or brazed to the wall plate 10.

A motor 20 is positioned within the opening 16 and protrudes beyond the vertical plane defined by the outer edge of flange 11.

Straps 21 and 22 surround the casing of the motor and are secured together at appertaining ends by bolts 23. A supporting rod or shaft 24 is welded or brazed to the upper strap 21. The shaft 24 rises from the strap in vertical direction and is offset inwardly to form a knee 25 and thence continues in vertical direction. To the upper end of shaft 24 is rigidly secured a link or arm 26 from which rises a bolt 27 projecting through an arcuate slot 28 in the top of the casing 8 defining a semi-circle. The bolt 27 is threaded at the top to receive a nut 29 which permits the shaft to be locked in adjusted position.

To the strap 22 a shaft 30 is secured by welding or brazing which is also offset to form a knee 31 and thence continues vertically downwardly in registry with the inner portion of shaft 24. The shaft 30 is journaled in a grommet 32 held by a bracket 33.

The shaft 34 of the motor 20 continues inwardly to carry a fan 35 which as shown in Fig. 4 when occupying the full line position acts as a ventilating fan. The nut 29 then is in the position shown in Fig. 5.

If it is desired to operate the fan as a suction or exhaust fan, the nut 29 is loosened and moved counterclockwise whereby rotation is imparted to shafts 24 and 30 by the crank arm 26, causing the fan to occupy the dotted line position shown in Fig. 4.

The casing 18 is open at the sides and front and has a screen 36 for the passage of air.

It is evident that the fan is supported to rotate about a vertical axis parallel to the central longitudinal axis of the fan blades so that the fan blades normally rotate about horizontal axis and may be also moving around about a vertical axis.

The modification shown in Figs. 7 to 9 differs from the previously described embodiment therein that the crank shaft is dispensed with and in lieu thereof a straight shaft employed.

As shown, the motor 36 is surrounded by straps 37 and 38 which are secured together at appertaining ends by bolts 39.

Vertical shafts 40 and 41 are respectively secured by welding or brazing to the straps 37 and 38.

To the motor shaft 42 is secured a fan 43.

The casing 44 has an arcuate slot 45 in which is guided a bolt 46 rising from a horizontal arm

47 which is below the upper casing wall and is rigidly secured to the shaft 40. The end of the bolt protruding from the casing carries a nut 48.

It is evident that upon moving the arm throughout the slot 25, the motor will be turned about 180° so that the fan instead of the full line position will be reversed to occupy the dotted line position shown in Fig. 8.

While the drawing shows two embodiments of the invention, numerous changes and alterations may be made without departing from the spirit of the invention.

I, therefore, do not limit myself to details of construction or arrangement of parts, as shown, but wish to include all modifications and revisions constituting departures within the scope of the invention, as defined in the appended claims.

I claim:

1. In a fan, a housing surrounding said fan, a crank shaft secured to said fan, means for rotatably supporting said crank shaft in said housing, a crank arm secured to one end of said crank shaft and a bolt on the free end of said arm and projecting through an arcuate slot in said housing.

2. In a fan, a housing surrounding said fan, a rod supporting said fan removed from the blade carrying end, an arm secured to one end of said rod, and a bolt extending from the free end of said arm through an arcuate slot in said housing.

3. In a reversible fan, a casing, a U-shaped rod having offset ends each mounted in an opposite wall portion of said casing whereby to afford a trunnion, a fan unit mounted in the bight portion of said rod trunnion, a crank connected to

one of said offset ends, an arcuate slot in the wall of said housing adjacent said crank, and a crank-operating element projecting from said crank through said slot for manual access to rotate the trunnion.

4. In a reversible fan structure, a casing, a pair of complimentary yoke pieces formed to clamp a fan unit therebetween, a rod secured to each said yoke piece and each said rod having an offset end portion, means for clamping said yokes together to secure a fan unit as aforesaid, with said rods defining a trunnion, said offset rod end portion being pivotally mounted in opposite wall portion of said casing whereby said fan unit may be rotated by said trunnion to reverse the air flow.

5. The structure defined in claim 4 and further characterized in that one of said offset rod ends is provided with a crank having a radially disposed handle member projecting through an arcuate slot in an adjoining wall portion of said housing for manual engagement to oscillate said trunnion between reverse positions.

SAMUEL M. BERNSTEIN.
